UNITED STATES PATENT OFFICE.

MABEL HARLOW, OF BOSTON, MASSACHUSETTS.

DESIGN FOR A DOOR-STOP.

48,747.

Specification for Design.

Patented Mar. 21, 1916.

Application filed January 21, 1916. Serial No. 73,481. Term of patent 3½ years.

To all whom it may concern:

Be it known that I, MABEL HARLOW, a citizen of the United States, residing at Boston, in the county of Suffolk and State of Massachusetts, have invented a new, original, and ornamental Design for Door-Stops, of which the following is a specification, reference being had to the accompanying drawing, forming part thereof.

Figure 1 of the drawing is a front elevation, and Figs. 2 and 3 are side elevations of a door stop showing my new design.

I claim—

The ornamental design for a door stop as shown.

MABEL HARLOW.
